United States Patent Office

Des. 196,362
Patented Sept. 24, 1963

196,362

SCREEN WALL BUILDING BLOCK

Frederick F. Bassetti, 14401 SE. 55th, Bellevue, Wash.

Filed June 4, 1962, Ser. No. 70,386

Term of patent 14 years

(Cl. D18—2)

FIGURE 1 is a front elevational view of a screen wall building block, showing my new design,

FIGURE 2 is a side view of a screen wall building block,

FIGURE 3 is a top view of a screen wall building block, and

FIGURE 4 is a perspective view of a screen wall building block.

I claim:

The ornamental design for a screen wall building block, substantially as shown.
